UNITED STATES PATENT OFFICE.

LOUIS TACKE, OF CHICAGO, ILLINOIS, ASSIGNOR TO H. SCHULTZ & COMPANY, OF CHICAGO, ILLINOIS, A CORPORATION OF ILLINOIS.

FEED ATTACHMENT FOR STAPLING AND OTHER MACHINES.

Application filed May 19, 1927. Serial No. 192,551.

This invention relates to improvements in stapling machines and more particularly for machines of this type which are used in paper box factories for attaching display cards to paper boxes.

The object of the invention is to provide a machine of this character which is equipped with mechanism for feeding the display cards consecutively into the desired position relatively to the stapling mechanism, including the anvil member thereof, to cause the same to be properly positioned relatively to the carton or paper box to which the said display cards are to be attached as said boxes are consecutively manually fed or positioned under the stapling head for attachment thereto of the display cards, the anvil member of the machine being provided with suitable gauges for engagement by the boxes to govern their position in the machine.

A further object of the invention is to provide a trip device associated with the display card feed mechanism to cause the latter to be operated following the completion of the stapling of the next preceding card to a box so as to insure the presence of a display card in the requisite position on the anvil member prior to feeding the next succeeding box upon the latter.

Another object of the invention is to provide mechanism of the above type referred to which may be easily mounted upon existing stapling machines of the particular type shown in the drawings in the form of an attachment thereto.

In the accompanying drawings I have illustrated the invention as embodied in the form of an attachment to stapling machines of the particular type shown, but wish it to be understood that the invention is not limited to such specific embodiment as it may, obviously, be variously embodied within the definition of the claims hereof to adapt the same to other stapling machines. In the said drawings:

Figure 1 is a side elevation of a stapling machine equipped with display card feed mechanism constructed in accordance with the invention.

Figure 2 is a front elevation of the upper portion of the same.

Figure 3 is a plan section of the same on the line 3—3 of Figure 1.

Figure 4 is a detail vertical section on the line 4—4 of Figure 3.

Figure 5 is a vertical section on the line 5—5 of Figure 3.

Figure 6 is a vertical section on the line 6—6 of Figure 5.

Figure 7 is a perspective view of a plunger employed.

Figure 8 is a fragmentary perspective view showing a cam element coacting with the plunger shown in Figure 7.

Fig. 9 is a detail vertical section on the line 9—9 of Figure 4.

Figure 10 is a detail fragmentary perspective view of the display card feeding plunger of the machine.

Figure 11 is a fragmentary detail perspective view showing the body member of the card feeding mechanism.

Figure 12 is fragmentary perspective view of a box or carton having a display card attached thereto.

The machine, in the instance illustrated, comprises the standard 1, the stapling head 2, the electric motor 3 and gearing between the latter and the stapling mechanism which includes the spur-gear 4 and a clutch 5 controlled by the foot-lever 6 to operatively associate the spur-gear 4 with the stapling mechanism.

Mounted upon the standard 1 and projecting to a point below the stapling head 2, is the anvil member 7 upon which the elements to be stapled together are supported. Adjacent the front end of the anvil member 7 and extending downwardly therefrom is a gauge-plate 8 against which the edges of the side-walls of the box or carton 9 bear to properly position an end wall of the latter upon the anvil member 7, the box or carton 9 being movable laterally of the anvil member while the edges of the side walls are maintained in contact with the plate 8.

Mounted upon the anvil member 7 is a plate 10 provided with a pair of parallel longitudinal slots 11 through which the

upper portions of feed shoes 12 project, the latter being carried by the cross-arm 13 of the reciprocable plunger 14 which is equipped with a rack-bar 15 meshing with the segmental spur-gear 16 pivotally mounted on brackets 17 of the guide block 18 secured to the anvil member 7 by means of bolts 19.

The plate 10 is equipped with an adjustable gauge plate 20 movable toward and from its front edge, and with a fixed upstanding side-edge flange 21 and an adjustable side plate 22 carried by the longitudinally slotted arms 23 secured by means of set-screws 24 to the bottom of the plate 10. The display cards 25 which are to be stapled to the end walls of cartons 9 are disposed, printed faces down, between the elements 21 and 22 with those edges thereof, which constitute their upper edges when mounted upon the carton 9, in contact with the gauge-plate 20. The elements 21 and 22 have their front vertical edges spaced from the front edge of the plate 10 a distance substantially equal to the length of the display cards between the upper and lower edges of the latter. Secured to the front edges of the elements 21 and 22 is a bar 26 equipped at one end with a longitudinal slot 27 for the reception of set-screw 28 for permitting adjustment of the plate 22, the lower edge of said bar 26 being parallel with and spaced from the top-surface of the plate 10 a distance slightly in excess of the thickness of a display card 25. This bar 26 carries flat springs 29 bearing at their free end portions upon the plate 10 and with an upstanding flat spring 30 for retaining the upper portion of a stack of display cards 25 in place.

It will be noted that the slots 11 of the plate 10 extend from a point in front of the bar 26 to a point behind the gauge plate 20, the stroke of the plunger 14 being such that the card engaging edges 31 of the shoes 12 move from a point behind the gauge plate 20 to a point in front of the bar 26, the said shoes projecting above the plate 10 a distance slightly less than the thickness of a display card 25. The said edges 31 are preferably the front and slightly beveled edges of removable steel plates mounted on the shoes 12.

As shown in Figure 11, the member 18, which consists of a relatively heavy casting machined to the extent required, is provided in its upper face with a T-shaped longitudinal guide groove 33 to receive the plunger 14 and rack-bar 15. The bottom wall of this groove is provided with a slot 34 through which the toothed portion of the segmental gear 16 passes to mesh with the rack-bar 15. In the front end of the member 18 there is a recess 35 which is substantially V-shaped and receives the body portion of the crank 36 of a shaft 37 which passes through a longitudinal groove 38 in the bottom of the

member 18. The handle portion 39 of the crank 37 projects through the arcuate slot 40 in the gauge-plate 8 and is disposed closely proximate to the outer end of the anvil member 7.

A connecting rod 41 associates the segmental gear 16 with the crank 42 of a shaft 43 journalled in a bearing 44 of a member 45 which is secured to the bracket 46 upon which the motor 3 is mounted. The shaft 43 is associated by means of mitre gears or pinions 47 and 48 with the shaft 49 journalled in the bearing 50 of the member 45. The shaft 49 is equipped with a sprocket wheel 51 associated by means of the sprocket chain with a sprocket wheel carried by the gear wheel 4. The sprocket wheel 51 is normally rotatable on the shaft 49 and is rigid with the clutch member 52 which is provided in the face thereof opposing the bearing 50, with an opening or recess 53. Keyed to the shaft 49 is a clutch member 55 provided with an annular groove 56 into which one end portion 57 of a lever 58 normally projects, the said lever 58 being pivotally mounted between its ends upon a projection 59 of the member 44. The end portion 57 of said lever is held in contact with the inner wall of the groove 56 by means of the spring 60. The said end portion 57 of the lever 58 is provided with a recess, the wall 61 of which constitutes a cam element.

Mounted in an opening in the clutch member 55 is a plunger 62 which is hollow and bifurcated at one end. A pin 63 spanning the opening housing the plunger 62 engages in the bifurcated end of said plunger and constitutes the seat for one end of the compression spring 64 which serves to project the plunger 62 into engaging relation to the recess or opening 53 in the clutch member 52. The normally projected end portion of the plunger 62 is cut away to render said end portion substantially semi-cylindrical and provide a beveled shoulder 65 for cooperation with the cam surface or element 61 of the end portion 57 of the lever 58 to retract said plunger against the action of the spring 64 out of engaging relation to the recess 53.

The crank shaft 37 is associated with the crank 66, one arm of which is pivotally mounted in the arm 67 of member 44 and the free end of the other arm of which rests upon an end portion of the lever 58, the arrangement being such that when the crank-arm 39 is moved toward the anvil 7, the crank 66 will turn the lever 58 on its pivot to throw the cam surface 61 of the end portion 57 of said lever out of engagement with the beveled shoulder 65 of the plunger 62 to thus cause the latter to engage in the recess 53 of clutch member 52 as the said recess 53 becomes opposed to the said plunger. Thus the two clutch members 52 and 55 are

caused to rotate in unison until the cam arm 39 is released and the cam element 61 thus returns to normal position and is engaged by the cam shoulder 65 of the plunger 62 to effect retraction of the latter.

While the operation of the feed mechanism will probably be understood from the foregoing description, a brief summary thereof is appended as follows:—

10 The gauge plates 20 and side plate 22 having been adjusted in position relatively to the bar 26 and side plate 21, respectively, to accord substantially with the size of the display cards 25, which are of the same 15 width as the inner width of an end wall of the receptacle 9, a stack of said cards is disposed upon the portion of the surface of the plate bordered by the elements 20, 21, 22 and 26. The motor 3 being in operation, 20 the operator first moves the crank-arm 39 to the left to the limit of its movement in the slot 40 and instantly releases the same. This movement of said crank arm causes the end portion 57 of the lever 58 to be raised out 25 of the path of the shoulder 65 of the plunger 62 which instantly engages the opposed face of the clutch member 52 and spring into the recess 53 of the latter as soon as the same becomes opposed to the said plunger. 30 Preferably a number of said recesses 53 are provided in order that the coupling of the clutch members 52 and 55 may be practically coincident with the lifting of the lever-end 57. The latter will rest upon the plunger 62 until the latter has made a partial revolution and then drops into its path so that upon completion of a single revolution of the clutch members the cam surfaces 61 and 65 will have passed each other to retract 35 the plunger 62 and stop the shaft 49 from further rotation, the pressure of the spring 64 serving to cause the end of the plunger 62 to act as a brake.

40 The rotation of shaft 49 obviously effects a rotation of the shaft 43 and crank 42 to effect a full forward and back stroke of the plunger 14 thus feeding the lowest display card 25 into proper position relatively to the anvil member 7 where it is yieldingly held by the springs 29.

45 The operator now places a carton 9 so that one end wall thereof overlaps the positioned display card 25, the contact of the edges of the side walls of the carton with the plate 8 effecting accurate relative positioning of the carton and display card. The foot pedal 6 is then depressed to effect a stapling operation of the machine, the carton then moved laterally to approximately the 50 point for the next stapling operation, which is then effected, this being repeated for as many staples as are desired to be used. Usually only two staples are so used and after the last stapling operation the operator removes the carton by a swinging movement

55 to the left during which the right hand operates the crank-arm 39 to effect positioning of the next succeeding display card as above described.

60 The mechanism of the invention effects a considerable saving in labor in that it eliminates the operation of hand feeding of each display card into position preceding the stapling operation and, in practice, it is found that an operator can more than double the 65 normal output of the machine.

65 It will be obvious, of course, that while I have illustrated the feed mechanism as applied to the particular type of machine shown and for the specific purposes of that machine, the said mechanism is applicable to machines other than stapling machines, and to all types of the latter by making such slight modifications as lie within the skill of a mechanic to adapt said mechanism to 80 the particular need of the user.

85 I claim as my invention:

90 1. In a machine for operating consecutively on successive sheets of material, a sheet feeding mechanism including a support for a stack of sheets, reciprocable means feeding the sheets consecutively from the bottom of the stack, a crank-shaft operatively associated with said devices for effecting reciprocation thereof, gearing between said crank-shaft and the drive-shaft of the machine, a spring-held clutch interposed between said crankshaft and said drive shaft, said clutch including a member provided 95 with a recess, a companion member provided with spring-held plunger normally engaging in said recess to effect uncoupling of said clutch member, and a spring-held manually operable clutch-control lever, the latter and said plunger equipped with cooperating cam elements for automatically effecting disengagement of said plunger from said recess when said control lever is in normal spring-held position.

100 2. A display-card feed attachment for box stapling machines including a slotted support for a stack of cards, a member disposed below said support and provided with guides, reciprocable feed mechanism operating through said slots and carried in said 105 guides, said feed mechanism including a rack-bar, a segmental gear meshing therewith, a crank-shaft and pitman associated with said gear, a shaft associated with the drive shaft of the machine, gearing between said shaft and said crank-shaft, a normally engaged clutch interposed between the said 110 shaft and drive-shaft of the machine, spring-held means for maintaining said clutch normally inactive, and a second crank-shaft associated with said spring-held means and manually operable to throw the latter out of controlling relation to said clutch.

115 3. A feed attachment for stapling machines including a bracket having two bear-

ings, a crank-shaft and a countershaft geared to rotate in unison journaled in said bearings, gearing between said countershaft and the driveshaft of the machine, a normally engaged clutch interposed in said gearing, a member mounted upon the anvil member of the machine, a segmental gear carried thereby, a pitman connecting said gear with said crank-shaft, reciprocable sheet feeding means operatively associated with said segmental gear, spring-held cam elements associated with the clutch for maintaining the same inactive and automatically effecting disengagement of the members thereof, and a lever for controlling said cam elements having a terminal for manual actuation disposed adjacent the anvil member for actuation simultaneously with the removal of stapled members from the machine.

4. A feed attachment for stapling machines including a member secured to the anvil member of the machine and provided with guide formations, reciprocable sheet feeding means mounted in said guide formations, a slotted support for a stack of cards disposed over the anvil member and the member secured thereto and arranged for maintaining the bottom card of the stack in the path of said reciprocable means, means on said support for permitting only the bottom card of the stack to be fed, springs for yieldingly retaining the fed card in predetermined position relatively to the anvil member, a crank-shaft operatively associated with said reciprocable means, gearing between the same and the drive-shaft of the machine, a clutch interposed in said gearing, and manually controlled means associated with said clutch for permitting rotation of the crank-shaft and automatically limiting the rotation thereof to a single revolution following each actuation of said manually controlled means.

5. A feed attachment for stapling machines including a member secured to the anvil member of the machine and provided with guide formations, reciprocable sheet feeding means mounted in said guide formations, a slotted support for a stack of cards disposed over the anvil member and the member secured thereto and arranged for maintaining the bottom card of the stack in the path of said reciprocable means, means on said support for permitting only the bottom card of the stack to be fed, springs for yieldingly retaining the fed card in predetermined position relatively to the anvil member, a vertically disposed gauge-plate associated with the anvil member and having a slot therein, a crank-shaft operatively associated with said reciprocable means, gearing between the same and the drive-shaft of the machine, a clutch interposed in said gearing, and manually controlled means associated with said clutch for permitting rotation of the crank-shaft and automatically limiting the rotation thereof to a single revolution following each actuation of said manually controlled means.

5. A feed attachment for stapling machines including a member secured to the anvil member of the machine and provided with guide formations, reciprocable sheet feeding means mounted in said guide formations, a slotted support for a stack of cards disposed over the anvil member and the member secured thereto and arranged for maintaining the bottom card of the stack in the path of said reciprocable means, means on said support for permitting only the bottom card of the stack to be fed, springs for yieldingly retaining the fed card in predetermined position relatively to the anvil member, a vertically disposed gauge-plate associated with the anvil member and having a slot therein, a crank-shaft operatively associated with said reciprocable means, gearing between the same and the drive-shaft of the machine, a clutch interposed in said gearing, and manually controlled means associated with said clutch for permitting rotation of the crank-shaft and automatically limiting the rotation thereof to a single revolution following each actuation of said manually controlled means.

LOUIS TACKE.
